No 18586

UNITED STATES PATENT OFFICE.

JOACHIM MAIDHOF, OF NEW YORK, N. Y.

DESIGN FOR DRESS-TRIMMING.

SPECIFICATION forming part of Design No. 18,586, dated September 4, 1888.

Application filed August 6, 1888. Serial No. 282,100. Term of patent 3½ years.

To all whom it may concern:

Be it known that I, JOACHIM MAIDHOF, of New York, in the county and State of New York, have invented and produced a new and original Design for Dress-Trimming, of which the following is a full, clear, and exact description.

Reference is to be had to the accompanying drawings, forming a part of this specification, in which similar letters of reference indicate corresponding parts in both the figures.

Figure 1 is a front view of a dress ornamented with my design, and Fig. 2 is a rear view of the body portion of the dress.

In carrying out the design, A represents a garment, upon the upper or body portion, A', of which a diamond-like figure, B, is represented, one portion, b, of the diamond figure appearing upon the front of the body and the other portion, b', upon the back. The diamond-like figure B is formed of a series of cord-like lines formed in circular figures d, which figures are arranged in pairs to represent triangular figures, which figures are united to complete the diamond-like figure by another set of cord-like lines, d', drawn to represent a series of connected circular scrolls arranged to represent a rosette. A series of ball-like figures, d'', are represented as dropping from the rosette-like figure, and below the ball-like figures conical figures d''' appear, representing fringeless tassels.

Around the collar portion C of the garment a series of single connected scroll-like figures, d'', are drawn. The representation of the ball-like and conical figures d''' and d''' likewise appear at the back of the dress as dropping from one angle of the diamond figure.

In front of the dress, below the waist portion, one triangular section, E, of the upper diamond-like figure is reproduced, including the ball and conical figures d''' and d''. At one diverging extremity of the said triangular figure E a straight scroll-like figure, E', is perpendicularly arranged, in imitation of a girdle, the figure being represented by grouping cord-like lines formed in circular figures d, as in the diamond-like figure, in pairs, one pair below the other, each pair represented as connected. Below the figures d, forming a part of the girdle-like figure, another set of cord-like lines are drawn, to represent a series of connected circular scrolls, e, arranged to represent a rosette. The girdle-like figure is completed by graduated ball-like figures e', represented as suspended from the rosette figure.

I claim—

A design for dress-trimming, as shown in the drawings and set forth in the specification.

JOACHIM MAIDHOF.
